UNITED STATES PATENT OFFICE

162,399

CRISPER

Robert K. Gibbs, Evansville, Ind., assignor to Tri-State Plastic Molding Co., Henderson, Ky., a limited partnership

Application June 2, 1948, Serial No. 146,722

Term of patent 14 years

(Cl. D44—1)

To all whom it may concern:

Be it known that I, Robert K. Gibbs, a citizen of the United States and a resident of Evansville, Indiana, have invented a new, original, and ornamental Design for a Crisper, of which the following is a specification, reference being had to the accompanying drawing, forming part hereof, in which:

Fig. 1 is a top plan view of a crisper embodying my new design;

Fig. 2 is a side elevational view with the lid in raised position;

Fig. 3 is an end elevational view; and

Fig. 4 is a partial sectional view thereof taken on line 4—4 of Fig. 1.

The dominant feature of my design resides in the configuration of the cooperating hand grip elements formed respectively at the ends of the two parts of the crisper.

I claim:

The ornamental design for a crisper, as shown and described.

ROBERT K. GIBBS.
